W. T. CAMPEN.
WHEEL GUARD FOR SAWMILL CARRIAGES.
APPLICATION FILED JUNE 4, 1912.

1,074,161.

Patented Sept. 30, 1913.

UNITED STATES PATENT OFFICE.

WILLIAM T. CAMPEN, OF SOUTH CREEK, NORTH CAROLINA.

WHEEL-GUARD FOR SAWMILL-CARRIAGES.

1,074,161.

Specification of Letters Patent. Patented Sept. 30, 1913.

Application filed June 4, 1912. Serial No. 701,644.

To all whom it may concern:

Be it known that I, WILLIAM T. CAMPEN, citizen of the United States, residing at South Creek, in the county of Beaufort and State of North Carolina, have invented certain new and useful Improvements in Wheel-Guards for Sawmill-Carriages, of which the following is a specification.

This invention relates to wheel guards for sawmill carriages, and has for its object the provision of a device of simple construction whereby all sawdust or other refuse which tends to lodge upon the track rail and accumulate thereon so as to obstruct the carriage and cause the same to travel in an uneven jolting manner will be effectually removed from the rail.

The invention also seeks to provide a device of simple and economical construction, in which the parts subjected to wear may be easily renewed and by which the wheel will be held in its upright position and prevented from rocking upon the track rail.

Other incidental objects will appear as the description of the invention proceeds, and the invention consists in certain novel features which will be particularly pointed out in the claims at the end of the description.

In the annexed drawings: Figure 1 is a view showing my improved wheel guard in longitudinal section, and illustrating the operative position of the same relative to the track rail and the wheel. Fig. 2 is a detail elevation of one member of the guard. Fig. 3 is a plan view of the guard. Fig. 4 is a detail perspective view of one of the wear blocks. Fig. 5 is a detailed bottom plan view of one end of the guard, the wear-plate being removed.

In the drawings, for illustrative purposes, I have indicated at 1 the lower portion of an ordinary sawmill carriage provided with a journal 2 on which a wheel 3 is mounted, said wheel running upon a track rail 4.

The wheel guard consists of two wrought iron sections 5 having their ends inclined to form or approximate plow points 6. Each section is provided on its inner face, adjacent its end, with an inclined rib 7, and remote from said rib is reduced to provide

the inclined shoulder 8 diverging downwardly from the rib and extending to a short transverse ledge 9, from which extends a vertical shoulder 10, the latter being carried to the lower end of a lug or projection 11 on the lower edge of the section, which lug extends transversely across the lower edge of the section to provide a stop 12 against which the wear block may rest. The upper edge of the section, between the ends thereof, is recessed, as shown at 13, to approximately conform to the rim of the wheel 3, and a segmental enlargement or offset 14 is provided on the inner face of the section immediately below the said recess, thereby presenting the curved shoulder 15 which is adapted to engage over the rim of the wheel, so that, when the two sections are brought together and engage opposite faces of the wheel, the latter will be maintained in its upright position and held against lateral swaying, so that it will not rock upon the track rail.

Between the opposed faces of the sections, at the ends thereof, I fit the wear blocks 16 which are so formed as to present shoes 17 adapted to ride upon the rails 4 and having their outer ends 18 shaped to conform to the plow points 6 of the sections. The inner ends of the shoes 17 are disposed at a right angle to their sides, as shown at 19, so as to fit squarely against the stops 12, which stops receive the thrust of the shoes during their travel and hold them in place.

A standard or body portion 20 rises centrally from the shoe 17 and is disposed longitudinally of the shoe, so as to fit between the ends of the sections 5, the front edge of the said body portion or standard being disposed inwardly from the extreme front end 18 of the shoe, so that the end of the shoe may project under the ends of the sections and the ribs 7 thereon and be thereby held against the tops of the track rails, as clearly shown in Fig. 1. The said standard or body portion is of such height as to extend to the top of the sections 5, and its upper end is so disposed as to lie flush with the surfaces of the upper edges of the sections, as will be readily understood. The front edge of the standard or body portion is beveled so as to

fit against the inner beveled faces of the ribs 7, and the lower portion of the rear edge of said body portion or standard rests against the vertical shoulders or ribs 10 of the sections 5.

Inclined ribs or offsets 21 are formed at the upper rear portions of the standard 20, and these inclined ribs or lugs rest against the inclined shoulders 8 of the sections 5, as shown most clearly in Fig. 3. The said inclined lugs or ribs 21 together constitute a shoe or wearing face 22 to be engaged by the wheel, the lower end of which projects rearwardly beyond the standard or body portion 20 and rests upon the ledge 9, as shown most clearly in Fig. 1. Alined openings 23 and 24 are formed through the sections 5 and the wear blocks to receive securing bolts 25 by which the sections are held together and the wear blocks secured firmly in position between the sections.

The wheel guards heretofore most commonly used were subjected to considerable wear on their inner faces from the sides of the wheel, and the opposed faces tended to wear unevenly, so that the wheel would sway or tilt laterally and rock upon the track rail, so that the carriage would be oscillated and the saw would produce an uneven cut. My construction overcomes these disadvantages, inasmuch as the segmental projections on the inner opposed faces of the guard sections engage the wheel over the rim of the same, so as to hold the wheel to the rail and prevent the rocking of the same. As the wheel is engaged equally upon its opposite sides, the wear will be even and consequently the life of the wheel and the guard both appreciably prolonged.

The face of the wheel being in contact with the faces of the wear blocks 16, will act thereon to cause the guard to move in the direction of movement of the carriage, and as the face engaged by the wheel is integral with the face running upon the track, the movement will be even and steady and all jolting of the carriage will be overcome. The travel of the guard over the rail effectually divides and throws to the sides any material tending to accumulate thereon, so that the wheel will always have a clean tread upon which to travel.

The construction of the wear block devised by me effectually holds the same in its place and provides abutments so as to resist any tendency of the block to oscillate in any direction. Should the wear block become unfit for further use through long continued wear, it is necessary merely to loosen the securing bolts and substitute a new block, which operation will require but a few minutes time.

The construction of my device is exceed-

ingly simple and it may be, therefore, produced at a low cost.

What I claim is:—

1. A guard for sawmill carriage wheels consisting of mating sections, and wear blocks secured between said sections at the ends thereof, the wear blocks having integral shoes extending under the ends of the sections and the sections being provided adjacent their ends on their lower edges with transverse stops against which the inner ends of said shoes abut.

2. A guard for sawmill carriage wheels comprising mating sections provided on their inner opposed faces with inclined abutting ribs at their ends and inwardly from said ribs with inclined shoulders diverging downwardly from the ribs and having transverse stops on their lower edges, and wear blocks secured between the ends of the sections and having shoes abutting the said transverse stops and extending therefrom under the lower edges of the sections to the outer ends thereof, said blocks bearing against the inclined ribs and having lateral lugs resting upon the said inclined shoulders.

3. A wear block for sawmill wheel guards comprising a shoe adapted to extend under the guard, a standard rising from the shoe and adapted to fit within the guard, and an inclined wear plate at the upper rear portion of said standard and projecting laterally beyond the sides of the same to be engaged by the periphery of the sawmill carriage wheel.

4. A wear block for sawmill wheel guards comprising a shoe adapted to extend under the guard, a standard rising centrally from the shoe and disposed longitudinally of the same, the lower portion of one end edge of the standard being vertical and flush with the corresponding end edge of the shoe and the opposite end edge of the standard being disposed short of the adjacent end of the shoe and inclined upwardly away therefrom, and lateral lugs on the sides of the standard adjacent the vertical end edge portion of the same and extending upwardly and inwardly from said portion toward the inclined edge of the standard.

5. A guard for sawmill carriage wheels comprising mating sections provided at their ends on their inner opposed faces with outwardly and downwardly inclined abutting ribs extending between the upper and lower edges of the sections and adjacent their ends on said faces with inclined shoulders diverging downwardly from said ribs, transverse ledges at the lower ends of said shoulders, vertical shoulders extending downwardly from said ledges and terminating in transverse stops below and extending under the lower edges of the sections, wear blocks comprising standards fitted between

the sections and against said ribs and said vertical shoulders, lateral inclined lugs at the upper rear corners of the standards fitting against said inclined shoulders and having their lower ends resting on said transverse ledges, and shoes rigid with the lower ends of the standards extending under the lower edges of the sections and having their lower ends abutting the said transverse

stops, and means for securing the sections 10 and the wear blocks together.

In testimony whereof I affix my signature in presence of two witnesses.

WILLIAM T. CAMPEN. [L.S.]
